UNITED STATES PATENT OFFICE.

ANTHONY PECORARO, OF NEW YORK, N. Y.

ADJUSTABLE DRESS-FORM.

1,375,316.

Specification of Letters Patent. Patented Apr. 19, 1921.

Application filed September 25, 1918. Serial No. 255,594.

To all whom it may concern:

Be it known that I, ANTHONY PECORARO, a citizen of the United States, and a resident of New York, in the county of New York and State of New York, have invented certain new and useful Improvements in Adjustable Dress-Forms, of which the following is a full, clear, and exact description, whereby any one skilled in the art may 5 make and use the same.

The invention relates to garment forms and more particularly to what might well be termed an adjustable dress form, in that it is adjustable as to its various elements to 15 produce figures of different sizes, with possibilities of providing adjustments for different portions of the torso represented by the figure.

The parts are so constructed and arranged 20 that any one of the sections may be moved and adjusted without affecting the adjustment of the other sections, thus making it possible to secure the actual shape as well as the correct size desired.

The object of the invention is to provide 25 a sectional or adjustable dress form with interengaging interlocking parts, adjustable with reference to each other and flexible in the adjustment of the relative parts, at the same time providing a grip for holding the 30 elements when adjusted.

A further object is to provide adjustability for a dress form in which the adjustments may all be effected from the outside 35 of the form, without necessitating the insertion of the hand of the operator to clamp the various parts.

A still further object is to provide a 40 clamping device for the parts of the dress form, which is flexible in character and which will firmly hold in any position of adjustment.

It is also an object of the invention to produce a very simple and efficient device 45 for adjustably holding the various elements of the form.

Referring to the drawings:

Figure 1 is a diagrammatic view of the front of the form.

Fig. 2 is a similar side view.

Fig. 3 is a similar rear view.

Fig. 4 is a developed view of the inside of the back.

Fig. 5 is a sectional view through a clip.

Fig. 6 is a similar sectional view through a clip at right angles to that of Fig. 5.

Fig. 7 is a sectional view of a waist clip.

Fig. 8 is a sectional view in different position from that of Fig. 7.

Fig. 9 is a horizontal section through the 60 form above the base plate.

Fig. 10 is a sectional view through a bar and retaining clip of the base.

Fig. 11 is a horizontal section at the neck of the figure. 65

Fig. 12 is a vertical section at the neck and its fastenings.

Fig. 13 illustrates a securing clip with an extended tongue for permanent fastening.

Fig. 14 illustrates a modified form of clip. 70

Fig. 15 is a top plan view of the washer for the clip of Fig. 14.

Adjustable dress forms *per se* are old in the art and have had their various sections or elements secured in various manners, 75 usually by clamp or locking devices arranged interiorly of the form. These have necessitated insertion of the hand and arm within the form to regulate the adjusting clamps or locks; and where a form is made up of numerous parts such as, for instance, a "twenty-four piece" form, it is difficult to locate the various locking devices and properly adjust them. 80

I am aware that friction clamps of one 85 sort or another have also been employed for holding the parts of dress-forms in place, but these ordinarily have either required hand manipulation to permit adjustment of the parts or have been combined with positive clamping devices or consisted of a clip bent into such a form as to bind. These, so far as known to me, have been more or less uncertain and unsatisfactory in practical operation. To overcome the difficulties, I have 90 introduced a distinct element in the form of a separate compression spring which abuts between one side of the clamping clip and against the bar which is to be held, forcing the bar against the opposite side of the clip 95 and insuring a most satisfactory resilient connection, giving some latitude of play, with the spring always under compression.

It is one of the principal objects of the present invention to overcome this difficulty 105 by providing what is substantially a universal form of lock or connecting device between the several elements of the form so arranged that the form is wholly adjustable from the exterior. Its parts may be pulled 110 apart or forced together to give any desired shape to the figure.

As illustrated in the drawings, the form consists of twenty-four distinct pieces, although the same adjusting devices might be employed on forms of different character.

5 As herein shown, there are two front neck pieces, 1, 2; two front shoulder pieces, 3, 4; the front neck pieces and shoulder pieces merging into the bust and waist sections, 5, 6, and front under-arm sections 7, 8. Below these are front lower sections 9, 10, and hip sections 11, 12. The whole figure is divided with a front medial line and a side under-arm line.

15 The back of the figure is made up of the neck and back sections 13, 14; back shoulder sections 15, 16; back sections 17, 18; and back and under-arm sections 19, 20. These sections are joined at the waist line by the hip sections 21, 22, and back sections 23, 24.

20 All of the various sections of the figure are adjustably held together by resilient clamp devices, as illustrated and more particularly and definitely shown in the detail figures of the drawings. The connecting and clamping devices, except those at the waist line, are substantially identical and consist of a spring bar of flexible character 25, which passes through a clamping clip 26, over a compression spring 27.

30 The clamping clip 26, is perforated to receive a fastening rivet 28, which is preferably arranged centrally of the clip and secures the lower end of the compression spring 27. This rivet is secured in the material of the form and also serves as a pivot upon which the clamping clip 26, may rock to give lateral adjustments as the bar 25, is withdrawn to a greater or less extent through the clip 26.

35 The bars 25, are secured at one end to the form; either by double rivets where it is desired to hold them in parallel relation, or by a single rivet where it is desired to give them a pivotal action with reference to the clip.

40 In any event, the bar is secured to one piece of the form while the clip is secured to the adjacent piece which is to be adjusted with reference to the part bearing against the bar. The ends of the bar are preferably fashioned so that they may be turned up to provide a stop, as at 29, to prevent the bars pulling out of the clip 26.

45 The adjusting devices at the waist line differ slightly from those used throughout the other parts of the form and, as illustrated, consist of a tapered clamping clip member 30, through which passes the bar 31. The bars 31, have an offset portion so that they will accommodate themselves to the tapered clamping clips 30, as the upper and lower sections about the waist line are withdrawn.

50 This gives a universal adjustment for the parts when it is desired to change the waist

line, either lengthening or shortening it or in fact enlarging the waist measurement, by opening up the various sections of the form.

55 In some instances, as illustrated, two of the bars are pivoted together and are disposed at an angle with reference to each other as they pass through their respective clamping clips, thus simplifying the number of parts and the application thereof to the form. All of the lower sections 9 to 12 inclusive and 21 to 24 inclusive are adjustably secured to a base-piece 32, by angle bars 33, one end of each being secured to its respective element of the form and the other end being passed through a retaining clip 34. These clips are pivotally mounted on the base so that they give freedom of adjustment to the bars 33, and their respective form sections. The base piece 32, has a central perforation through which is passed the supporting standard.

60 The base-piece is imperforate except for the opening for the standard and the pivots of the clamps and does not require slotting to secure adjustment of the various elements 90 named, as is the case in most dress forms where clamps and similar devices are employed.

65 This standard, as illustrated, terminates in a neck piece clamp 35, which has an extended boss 36, into which the end 37, of the supporting standard 38, extends, thus permitting the dress form to be rotated upon the supporting standard.

70 The neck piece clamp 35 is similar in form and operation to the clamps heretofore described and consists of right angle channels 39, 40, intersecting each other at the central point and each provided with a compression spring 41. Through these channels 100 extend angle bars, there being a bar for each neck section, having one end of the angle attached to the neck section and the opposite end extending through a channel of the neck bar clamp. It is preferred that 105 these bars overlie each other in regular sequence to give the best clamping effect. For instance, the two bars passing through the channel 39, have one of the bars passing through the channel 40, extending between 110 them, while the second bar overlies them.

75 The clamping clips 26, are of simple construction and consist of stamped-up metal channels open through their longitudinal line as at 26^a, and thus providing two resilient lips or flanges 26^b, against the under side of which bears the clamp bar 25. The spring 27, being located directly below these lips 26^b, forces the bar 25, firmly against the underface of the lips 26^b, with sufficient 125 force to firmly clamp them, although permitting a withdrawal of the bars when sufficient force is applied longitudinally thereof.

80 The modified form of clamping clip illustrates a compression spring member 50, as 130

surmounted by a washer 51. This washer is pressed up from sheet metal and has projecting fingers 52, that extend within the coils of the spring and holds the washer in place, or its center may be forced out to provide a catch-button 53. This may be employed in conjunction with a perforation at the end of the coöperating clamping bar to prevent complete disengagement of the bar and clip. The body of the clamping clip 54, is of the same form and construction as heretofore described and, in either of the forms of the device, the compression spring is relied upon to firmly clamp the sliding bar against the under side of the upper lips of the clamp.

Where it is desired to prevent rotation of the clamping clip, its lower edge may be extended as at 28^a, and a second rivet placed 20 through the perforation 28^b.

It will be apparent from the above that there is a separate adjustment for the neck, shoulder, back, bust, under-arm, and hip measurements. It may be made long or 25 short waisted; the shoulders may be regulated for greater or less length, square or sloping. The bust is also adjustable without changing the back or other measurements. The hips may be made wider without changing 30 measurements from front to back or vice versa. In fact, there is substantially a universal adjustment to meet all requirements and all these adjustments may be effected from the exterior of the complete 35 form, and, when once adjusted, will hold their position through the action of the clamp devices until re-adjusted.

Obviously, various modifications of the device might be made without departing 40 from the spirit or intent of the invention, which is directed to securing a firm, though adjustable, clamp between the various elements of the form, permitting an adjustment of the parts of the form from the exterior thereof and insuring a tight holding 45 of the parts when once adjusted.

What I claim as my invention and desire to secure by Letters Patent is:

1. An adjustable dress form comprising 50 a plurality of body sections, a base-piece therefor, a resilient clamp for the neck sections having an extended boss providing a socket, and a standard extending through the base section and engaging the socket of the resilient clamp.

2. An adjustable clip for the body-parts of a dress form consisting of a clip member having a channel therethrough, a spiral compression spring secured within the chan-

nel, and a sliding bar resiliently clamped between the spiral spring and clip.

3. An adjustable clip for the body-parts of a dress form comprising a clip member having a channel extending therethrough, a sliding bar extending through the channel, 65 a coiled compression spring compressed by the sliding bar against the bottom wall of the clip, and a rivet extending through the spring and clip for securing the parts.

4. An adjustable clip for the body-parts 70 of a dress form consisting of a stamped-up channel having a longitudinal opening providing clamping lips, a coiled compression spring arranged within the channel, a pivot for securing said compression spring and 75 stamped-up channel, and a sliding bar bearing against the inner side of the lips and forced thereagainst by the compression spring.

5. An adjustable clip for the body-parts 80 of a dress form consisting of a stamped-up channel having a longitudinal opening providing clamping lips, a coiled compression spring arranged within the channel, a pivot for securing said coiled compression spring 85 within the channel, a sliding bar bearing against the inner side of the lips and forced thereagainst by the compression spring, and means upon said bar for preventing disengagement of the bar and clip.

6. An adjusting device for dress forms consisting of a channeled clamping member, an adjusting bar extending through said channel, a coiled compression spring secured within the channel, and a washer intermediate the compression spring and bar, said washer provided with means for preventing disengagement of the washer and spring and having a central extension forming a catch button for the bar.

7. An adjusting device for the body-parts of a dress form consisting of a slideable bar attached to one section of the form, a clip attached to the adjacent section thereof and having a channel through which the sliding 100 bar extends, a coiled compression spring resting between the inner wall of the channel of the clip and bar for resiliently holding the parts in various positions of adjustment, and pivoted means incident to the fastening of the clip and bar permitting lateral adjustment as well as longitudinal adjustment of the parts.

ANTHONY PECORARO.
